UNITED STATES PATENT OFFICE.

SIMEON C. LAWLOR, OF CHICAGO, ILLINOIS.

MOP-WRINGER.

1,085,346.

Specification of Letters Patent.

Patented Jan. 27, 1914.

Application filed March 23, 1912. Serial No. 685,739.

To all whom it may concern:

Be it known that I, SIMEON C. LAWLOR, a citizen of the United States, residing at Chicago, in the county of Cook and State of Illinois, have invented certain new and useful Improvements in Mop-Wringers; and I do hereby declare the following to be a full, clear, and exact description of the invention, such as will enable others skilled in the art 10 to which it appertains to make and use the same.

This invention relates to improvements in wringers of the class especially designed and adapted for wringing mops, and one of the 15 objects in view is facilitating the relative adjustment of the wringer rollers for effecting easy access for the mop to be wrung.

With this and further objects in view, as will be in part hereinafter pointed out, and 20 in part become obvious, the invention comprises certain novel constructions, combinations and arrangements of parts as herein specified and claimed.

In the accompanying drawings, Figure 1 25 is a perspective view of a wringer embodying the features of the present invention. Fig. 2 is a similar view of the same taken from a different point of observation and showing the pivoted roll in its raised position. Fig. 3 is a view in side elevation of a fragment of the parts, a portion of the receptacle being seen in vertical section. Fig. 4 is a detail, edge view of one of the foot clamps, part of the clamping rod being 30 broken away. Fig. 5 is a similar view of a fragment of the clamping rod for one of the side frames. Fig. 6 is a detail, fragmentary view of the pivoted end of the pivoted roller, the bearing being seen in section.

Referring to the drawings by numerals, 1 40 indicates a receptacle at opposite sides of which are arranged side frames, each consisting of a plate 2, a clamping rod 3 and connected parts. Each plate 2, at its lower 45 end, is provided with outstanding eyes 4 and 4'. Through eye 4 extends the upper end portion of the rod 3, which portion is threaded and engaged by a nut 5, above the eye. The lower end of each rod 3 is formed 50 with a hook 6, which extends beneath and about the lower flange of the receptacle 1, whereby threading nut 5 downwardly will cause the nut to engage the respective eye 4 and pull down on plate 2. Each plate 2 55 is formed with an offset 7, at an intermediate portion, overhanging the upper edge of

receptacle 1, and a part of the offset portion is preferably struck down to form a hook 8 extending inside the upper edge of receptacle 1. Thus the tightening of nut 5 will 60 cause the hooks 6 and 8 of the respective side frame to clamp the respective plate 2 firmly in place.

That portion of each of plates 2 upstanding from the offset 7 is formed with a vertical slot 9 through which extends the respective journals 10 of roller 11. The journals 10 are thus free to move up and down within the limits of slots 9, but the said journals are normally held at the upper ends of the 70 slots by spring pressed rods 12, 12, each formed with an eye 13 surrounding the respective journal and extending downwardly from the eye through eye 4', and being surrounded by a coiled spring 14 whose lower 75 end rests upon eye 4', and whose upper end presses upwardly upon nut 5. Said nut 5 is threaded onto the respective rod 12, and is adapted to be threaded along the said rod for varying the tension of the spring 14, 80 and thus proportionately varying the upward pressure exerted by roller 11. The eyes 13 are spaced from the respective plates 2, and the intervening portions of journals 10 are engaged by the eyes of a bail 16 by 85 which the receptacle 1 may be lifted about.

Arranged somewhat above and slightly at one side of roller 11 is the cooperating roller 17 whose journal 18 at one end extends beyond its bearing and is formed with a 90 crank provided with an operating handle 19. The other journal, 20, of roller 17 is journaled in a sleeve bearing 21 which is formed with a depending eye 22 through which is passed a pintle 23. The pintle 23 95 is carried by eyes 24, 24, formed at the upper end of one of the plates 2, the intermediate eyes 24 being spaced apart for accommodating the interposed eye 22, and the end eyes 24 are spaced from the intermediate eyes 100 for accommodating the coils 25 of a spring formed of a spring wire or rod with its end portions lying along and inside of the respective plate 2 and its intermediate portion, between coils 25, looped to form a 105 spring finger 25''. The finger 25'' is so disposed that the loop surrounds the outer end of journal 20 and exerts a downward pressure thereon when roller 17 is in operative position, so as to impart a tendency to said roller to swing upwardly on pintle 23 as a pivot whenever the roller 17 is released. 110

The spring finger 25" is illustrated in Fig. 3 in full lines as in an expanded or exhausted position: that is to say, the coils 25 have unwound so far as their spring expansive tendency requires, and the finger is thus left outstanding and inert, leaving the roller free for a limited amount of pivotal movement. However, on swinging the roller downwardly, the upwardly moving journal 20

10 will engage the finger 25" and in the continued upward movement of the journal will place the finger under such spring tension as to enable it to elevate the free end of the roller 17 when released.

15 The plate 2, opposite that provided with eyes 24, is formed with a preferably somewhat inclined, upwardly opening, slot or notch 26 whose lower end forms the bearing for the journal 18. A locking pawl 27 is disposed for closing the notch 26 and completing the bearing, and thus confining the roller 17 against upward movement except when released. Pawl 27 is pivoted at 28 to plate 2 and is formed with a somewhat 20 arcuate notch 29, corresponding in curvature to the line of the arc through which the notch travels when the pawl is swung upon its pivot. For facility of operation, an operating lever 30 projects beyond the pivot 28 from the pawl 29, and an actuating spring 31 engages the lever 30 for normally retaining the pawl in journal-engaging position. The spring 31 has its end, opposite that which engages the pawl, connected to the 25 plate 2, and is formed with an intermediate coil 32.

The lower end of each of the rods 3 is preferably bifurcated, one branch of the bifurcation extending downwardly, as at 34, 40 and being provided with a bolt 35 which serves as a journal for a bail-like strap 36, the end portions of the strap pivotally engaging the bolt 35, and the intermediate portion of the strap being bent outwardly and 45 rigidly engaged by a tread plate 37, which serves, in operation, as a means for facilitating the prevention of tilting of the receptacle by the placing of the foot of the operator on said tread plate.

50 It is, of course, desirable to support the scrubbing receptacle or bucket spaced above the floor, and to this end I provide supporting feet for the bucket, preferably three in number, spaced uniformly about the receptacle. Each of these feet consists of a foot portion proper 38, formed preferably of a bent rod, the upper or upstanding portion of which is rigidly engaged by a plate 39 whose lower end portion is formed into an inwardly turned hook 40, and whose upper end portion is formed into an outstanding eye 41. Hook 40 is designed to fit about the lower flange of the receptacle 1, and a clamping rod 42 has its lower end portion 55 extending through the eye 41, and is thread-

ed and engaged by a nut 43 beneath the eye 41. The upper end portion of rod 42 is formed into a hook 44 extending over the upper end of the receptacle 1. By tightening the nut 43, it will be seen, the foot is easily and readily, as well as firmly and effectively clamped in place for supporting the receptacle, and may be as readily and quickly detached therefrom.

In operating the wringer, assuming the parts to be in the position indicated in Fig. 2, the mop is laid over the roller 11 with the major portion of the mop hanging down into the receptacle 1. It is noted that the guides 45, 45, fixed to the inner faces of the plates 2, serve to direct the mop for preventing the edges thereof from missing the roller. The operator then grasps the handle 19 and pulls the roller 17 downwardly until the journal 18 passes beneath the pawl 27 down the notch 26. The front edge of the pawl, above its notch 29, is rounded for causing the pawl to back off as the journal 18 is forced down the notch 26, but if the friction is found inconveniently great, the operator may depress the lever 30 and thus facilitate positioning the journal 18 at the lower end of notch 26. As soon as the journal has arrived in this position the pawl 27 springs back over the journal and effectively prevents escape thereof. It is noted here that the incline of the notch 26 is such that journal 18 cannot escape in a vertical line, and movement of the journal in the line of the notch 26 is directly in the line of the pivot 28 and must, therefore, be in the line of direct pull against the pawl, which the pawl will resist without reference to the pressure of the spring 31. It is, of course, obvious that in thus forcing the roller 17 down upon the mop (the roller 11 will have been forced downwardly against the tension of the springs 14. In this position, the parts are ready for the wringing operation which is accomplished by manually rotating the roller 17 in a direction for feeding the mop upwardly, and thus exuding the fluid from the mop and discharging it down into the receptacle.

I claim:—

1. In a mop wringer, the combination of side plates adapted to be disposed at opposite sides of a receptacle, a wringer roller having journals sustained by said plates, one of the plates being formed with an upwardly opening notch providing a bearing for one of the journals of the roller, a bearing for the other journal of the roller pivotally connected to the other plate, and a spring disposed for pressing the roller in a direction tending to lift the notch engaging journal out of the notch.

2. In a mop wringer, the combination of side plates adapted to be disposed at opposite sides of a receptacle, a wringer roller

- having journals sustained by said plates, one of the plates being formed with an upwardly opening notch providing a bearing for one of the journals of the roller, a bearing for the other journal of the roller pivotally connected to the other plate, a spring engaging the last mentioned plate and journal and pressing the journal in a direction tending to cause the roller to swing upwardly on the pivot, and a cooperating roller carried by said plates.
3. In a mop wringer, the combination of supports, a journal bearing sleeve pivotally connected to one of the supports, a roller having a journal mounted in said sleeve, the other support having a notch adapted to serve as a bearing and the roller having a journal mounted therein, a spring coiled about the pivot of the bearing sleeve and connected to the respective support carrying said sleeve, said spring having an intermediate portion looped over the journal of said roller and engaging the same under spring pressure tending to swing the roller on the pivot of said bearing sleeve, and a cooperating roller carried by said support.
4. In a mop wringer, the combination of spaced supports, one being formed with an upwardly opening notch adapted to serve as a journal bearing, a journal bearing sleeve pivoted to the other support, a wringer roller having a journal mounted in said sleeve and a journal adapted to extend through said notch, a spring engaging the former journal and pressing the same in a direction tending to elevate the latter journal out of the notch, and a pawl pivoted to the notched support and adapted to be swung across the notch for retaining the roller against pivotal movement, and a cooperating roller carried by said supports.
5. In a mop wringer, the combination of side plates adapted to be disposed at opposite sides of a receptacle, each of said side plates being substantially vertical and formed with a substantially horizontal offset intermediate its ends, the upper end portion of each plate being above the interior of the receptacle and the lower end portion being outside thereof, the offset being adapted to overhang and engage the upper edge of the receptacle, means connected with the side plates adapted to engage lower portions of the receptacle for drawing downwardly upon the side plates, and wringer rollers carried by the side plates.
6. In a mop wringer, the combination of side plates adapted to be disposed at opposite sides of a receptacle, each of said side plates being substantially vertical and formed with a substantially horizontal offset adapted to overhang the receptacle, means connected with the side plates adapted to engage lower portions of the receptacle for drawing downwardly upon the side plates, the horizontal offset portion of each side plate having a part of its material struck downwardly in position for extending within the receptacle, and wringer rollers carried by the side plates.

In testimony whereof I affix my signature in presence of two witnesses.
